M. LACHMAN.
CONSTRUCTION OF SHEET METAL DOORS.
APPLICATION FILED MAY 6, 1913.

1,109,233.

Patented Sept. 1, 1914.

UNITED STATES PATENT OFFICE.

MAURICE LACHMAN, OF NEW YORK, N. Y.

CONSTRUCTION OF SHEET-METAL DOORS.

1,109,233.

Specification of Letters Patent.

Patented Sept. 1, 1914.

Application filed May 6, 1913. Serial No. 765,779.

To all whom it may concern:

Be it known that I, MAURICE LACHMAN, a citizen of the United States, and a resident of New York, in the county of New York and State of New York, have invented certain new and useful Improvements in the Construction of Sheet-Metal Doors, of which the following is a specification.

This invention relates to the construction of sheet metal doors and particularly to the manner of assembling the same and joining the stile sections to the central or panel section.

The object of the invention is to simplify the method of making doors of sheet metal and to cheapen the construction so that this type of door will be capable of more successfully competing with wooden doors from a cost standpoint.

Another object of the invention is to provide a standard construction for doors of various sizes and to provide a construction that will lend itself to the production of doors of differing sizes without the necessity of providing separate tools or measurements for each size of door desired to be made.

By practising this invention it is not necessary to specially fit or mate the panel with the stile sections as is the case when doors are constructed by riveting the panel to or folding it with a part of the stile sections.

Also by this invention a very rigid structure is attained which lends itself to the application of a smooth, even finish to all parts of the door, that is at all times the desirable object in sheet metal door constructions.

The invention consists in the improved construction of sheet metal doors as herein-after more particularly described and then specified in the claims.

In the accompanying drawings Figure 1 is a front elevation of a metallic door constructed in accordance with this invention. Fig. 2 is an enlarged transverse section of the same and taken on the line 2-2 of Fig. 1. Fig. 3 is a cross-section through the blank from which the stile section is formed. Fig. 4 is a cross-section on a further enlarged scale and illustrates the joint between the stile and the panel. Fig. 5 is a detached side elevation of the welding strip used to join the parts together. Fig. 6 is a cross-section through one side of a door having double panels.

1 and 2 indicate the side stile sections of

a door while 3 and 4 indicate the top and bottom end stiles respectively. After the door is assembled the stiles 1, 2, 3 and 4 may be secured to each other along the meeting edges 5 in any suitable manner as by soldering, brazing, or other means as well known in the art. The stile members or sections are each preferably formed in the same manner from a blank of sheet metal preferably formed at each edge with a molding member 6 of any desired conformation. The blank as shown in Fig. 3 is preferably formed by stamping in a suitable press and a flange 7 projecting from each edge of the molding members 6 is also provided. The flanges 7 terminate in a depending skirt or flange 8 for the purpose hereinafter referred to.

While the stile section is still in the form shown in Fig. 3 a metallic strip 9 of relatively heavy metal is placed in the corner formed by the junction of the flanges 7 and 8 and welded to the flange 7. The strip 9 which is of the same thickness as the depth of the flange 8 is provided along each edge of the stile member. The preferable manner of securing the strip 9 to the flange 7 is by electrically welding it thereto and to assist in such welding operation the strip 9 is provided on its upper surface with a plurality of welding nibs or projections 10. As will be readily understood by those skilled in the electric welding art, the nibs or projections 10 are placed in contact with the flange 7, the strip and flange being held between a suitable current carrying electrodes. Upon the passage of an electric current from one electrode to the other the nibs 10 coalesce and on the application of pressure, preferably through the electrodes, the nibs are forced into the metal of the flange 7 and form a number of separated spot welds therewith. By providing the turned-over edge or flange 8 any buckling or rough edge on the flange 7 is avoided, as when attempting to weld the surface of the flange, if it had a free edge, the softening of the metal and the applied pressure will cause a buckling of the flange and a rough edge will result. This feature is not broadly claimed herein but is made the subject of claims in another application for patent filed by me herewith. The flange 8 also serves to conceal the welding strip 9 in the finished product. The welding strip 9 is also provided on its under surface with a plurality

- of nibs or projections 11 preferably arranged in staggered relation to the nibs 10 so as to permit a flat contact for the welding electrode when employed to weld the nibs 10 to the flange 7. After welding the strips 9, the blank is bent or folded at the points 12 to bring the two faces of the stile section parallel and form the edge 13 of the stile member.
10. 14 indicates the panel section which, owing to the manner of joining the parts together, may be of indefinite size and may comprise either a single thickness of metal as indicated in Figs. 2 and 4 or a double thickness spaced apart as indicated in Fig. 6. The welding nibs 11 of the strip 9 along each inner edge of the stile section are brought into contact with the surface of the panel 14 opposite each other and at any desired part of the surface of said panel according to the size panel or door desired. After being brought into contact the parts are engaged by suitable welding electrodes and current passed from one to the other 25 and the nibs 11 welded to the panel 6 by the application of pressure as will be readily understood by those skilled in the art. The panel 14 and the stile are thus firmly secured together and a smooth surface for the application of the finish is provided. The free ends 15 of the panel 14 project to a greater or less extent into the space within the stile sections and by this construction it is not necessary to accurately measure or fit the 30 panel to the stile, thus providing a uniform or standard size stile which can be employed for all sizes of doors within a proper radius.
- Referring to Fig. 6, when two panel members are employed they are preferably spaced apart as by blocks 16 and the space may be filled with any sound-deadening material desired as is usual in this art.
- The molding members 6 and flanges 7 may be suitably mitered in the corners as 45 at 17 and soldered, brazed or joined in any desired manner.

What I claim as my invention is:—

1. In a sheet metal door, a panel, a stile

section having an inwardly projecting flange, and a metallic strip between said flange and the surface of said panel welded to both said flange and said panel to secure said stile to the panel.

2. In a sheet metal door, a panel, a stile section provided with a molding along the inner edge, a flange projecting inwardly from said molding and a relatively heavy solid metal strip between said flange and said panel, said strip being welded to the face of the panel and to the flange.

3. In a sheet metal door, sheet metal stile sections provided with inwardly projecting moldings, a panel having free edges extending into the space within the said stile sections and a strip of relatively heavy metal welded to both the molding and the panel to join the stile to the panel.

4. In a sheet metal door, a panel section, a stile section having inwardly projecting flanges on opposite sides of said panel and a metallic strip on each side of said panel between said flange and the surface of the panel, said strips being welded to said flanges and the panel.

5. In a sheet metal door, a panel section having free edges, a one-piece stile section having an integral molding on opposite sides of the panel, a flange projecting from said molding and a welding strip between said flange and the surface of the panel, said strip being welded to both the flange and the panel.

6. In a sheet metal door, a panel section, a stile section having an inwardly projecting flange and a metallic strip between said flange and the surface of said panel and welded to said flange and said panel, the edge of said flange being turned over against the side of said strip.

Signed at New York in the county of New York and State of New York this 5th day of May A. D. 1913.

MAURICE LACHMAN.
